United States Patent Office.

WILLIAM G. REED, OF CHELSEA, MASSACHUSETTS.

Letters Patent No. 89,075, dated April 20, 1869.

IMPROVEMENT IN CHIMNEYS.

The Schedule referred to in these Letters Patent and making part of the same.

To all whom it may concern:

Be it known that I, WILLIAM G. REED, of Chelsea, in the county of Suffolk, and State of Massachusetts, have invented a Chimney-Building Block, of which the following is a full, clear, and exact description, reference being had to the accompanying drawings, making part of this specification, in which—

Figure 1 is a perspective view of one of my blocks, provided with smoke and ventilating-flues.

Figure 2 is a vertical section through the centre of the same.

Figure 3 is a horizontal section on the line $z z$ of fig. 2.

Figure 4, detail to be referred to.

My invention consists in a chimney-building block, provided with suitable smoke and ventilating-flues, by the employment of a series of which, properly united, a superior chimney may be constructed in a thorough and expeditious manner, and at a reduced cost.

To enable others skilled in the art to understand and use my invention, I will now proceed to describe the manner in which I have carried it out.

In the said drawings—

A represents a block of fire-clay, cast-iron, or other suitable material, of octagonal form in cross-section, the plane of the upper surface of which is accurately formed at right angles to that of each of the sides.

B is a central cylindrical tube, or pipe, which serves as a flue for conducting the smoke, &c., from the fire, up out of the building.

Upon the lower end of this smoke-flue is cast a circular lip, or projection, *a*, which snugly fits into a circular groove, or depression made in the block next below it, this circular groove being similar to that, *b*, in the top of the portion of the smoke-flue in the block A.

Surrounding this smoke-flue is a series of spaces, or chambers, which form portions of ventilating-flues C, separated by ribs, or partitions *c c*, the said ventilating-flues preventing the radiation of the heat of the smoke-flue to the exterior shell, or casing *d* of the block, and thereby precluding the possibility of the burning of the wood-work around it.

D is an opening through one of the ventilating-flues, and communicating with the interior of the central smoke-flue, a suitable thimble, *d*, being snugly fitted into this opening, for the reception of the end of the smoke-pipe passing through the plastering, and leading to the fire-place in one of the rooms.

E is an opening, similar to D, for the reception of a thimble, *e*, which communicates with one of the ventilating-flues, C. Into this thimble *e* is snugly fitted one end of a pipe, which passes through the plastering, and leads to the upper or lower part of the room to be ventilated.

Instead of openings D E for the reception of the thimbles *d e*, passages may be formed by casting them in the same piece as the block, in a manner similar to

the construction of the central smoke-flue, the outer end of the smoke-pipe passage being grooved out like the top of the smoke-flue, for the reception of a short pipe, with or without a shoulder, as shown in figs. 4 and 5.

The material of which the smoke-pipe is composed should be clay, or other suitable non-conductive material, as it will not rust or be destroyed by heat, but, for the ventilating-pipes, tin or sheet-iron will answer.

Any number of ventilating-flues may be formed, and several of these blocks, slightly modified in their construction, may be united, and constitute a chimney-stack.

When made of cast-iron, these blocks may be secured together by bolts, or otherwise, but, when made of clay, &c., they may be placed one upon another, with or without the use of mortar or cement; but I prefer to lute the joint, or connection between the circular lip, or projection *a* and groove, or depression *b*, in order to afford additional security against fire.

A chimney may be constructed of the blocks above referred to at an expense not exceeding that of an ordinary brick chimney, while, owing to the cylindrical form and smoothness of the interior of the smoke-flue, the draught is much better, and the soot is effectually prevented from lodging thereon; while the common brick chimney, of a rectangular cross-section, presents angles, into which the cool air presses downward against the column of ascending heated air, and partially impedes the progress of the smoke in its escape from the building. The spreading of the mortar used in laying the brick roughens the inner surface of the flue, and the soot, by accumulating thereon, still further obstructs the draught of the smoke upward, and a necessity arises of cleaning out the chimney, which my improved smoke-flue avoids.

By making the ventilating-flues outside the smoke-flue, I am enabled to economize valuable space in each of the rooms, and I am enabled to use a less quantity of material in the outer shell, and, at the same time, insure against the occurrence of fire, oftentimes liable to occur when wood-work is in contact with the brick chimney, or where the joints between the bricks are not tightly closed with mortar.

The number and position of the ventilating-flues may be varied to suit the requirements of the case, and the smoke-pipe may pass through one of the ribs, or partitions *c c*, into the smoke-flue, thereby avoiding the contraction of one of the ventilating-flues, and a ventilating-pipe may enter the same ventilating-flue either above or below the smoke-pipe, passing through it if desired; but I prefer to carry the smoke-pipe through a different ventilating-flue, or to carry it through one of the ribs, or partitions.

In the ordinary construction, should we wish to use a smoke-flue for ventilating-purposes, the opening for the ventilating-flue seriously interferes with the efficiency of the smoke-flue, and checks the draught of the

stove, and more or less smoke is liable to issue through the ventilating-flue into the room; but, by the employment of my improved block, I am enabled, in addition to the advantages possessed by the smoke-flue, to obtain one or more ventilating-flues superior in efficacy to and without occupying as much room and with less expense than those built independently of a smoke-flue in the ordinary way, the heat from the smoke-pipe being radiated into the ventilating-flues, and creating a constant upward draught, or current of air through the ventilating-flues.

My improved blocks may be built up in a vertical direction, or they may be slightly modified in construc-

tion, so as to be laid in a direction inclined thereto, and be supported by suitable framework, without departing from the spirit of my invention.

Claim.

What I claim as my invention, and desire to secure by Letters Patent, as a new article of manufacture, is—

A chimney-building block, provided with smoke and ventilating-flues, substantially as and for the purpose described.
